UNITED STATES PATENT OFFICE.

FRED M. LOCKE, OF VICTOR, NEW YORK.

ELECTRIC-ARC EXTINGUISHER.

1,127,043.

Specification of Letters Patent.

Patented Feb. 2, 1915.

Application filed July 31, 1914. Serial No. 641,536.

To all whom it may concern:

Be it known that I, FRED M. LOCKE, a citizen of the United States, and resident of Victor, in the county of Ontario and State 5 of New York, have invented certain new and useful Improvements in Electric-Arc Extinguishers, of which the following is a specification.

This invention relates to arc-extinguishers 10 of the type in which explosive or expansive action is employed to break the arc and reference is hereby made to my copending application Serial No. 686,554, filed March 27, 1912.

15 The object of the invention is to improve arc-extinguishers of this type in such a manner as to render them more effective. I have found that this may be done by employing the blast from an explosive cartridge to completely eject, from the path of the arc, a conductor forming part of the circuit, the arc being thus lengthened at two points simultaneously, and more effectually extinguished than where the blast from the cartridge is 20 employed merely to produce a single break in the arc.

25 In the drawings: Figure 1 is a diagram showing insulators and lightning arresters of a high-potential line, equipped with arc-extinguishers embodying the present invention; Fig. 2 is a similar diagram which shows another arrangement of the arc-extinguishers; Figs. 3 and 4 are elevations showing other modifications; and Fig. 5 is a 30 longitudinal section of the cartridge.

35 In Fig. 1, the insulators 4, 4, 4, are provided with upwardly-projecting lightning arresters of the form usually employed. The theory of these lightning-arresters is that 40 the arc, when one occurs, forms between the elbows 6, 6, and works upwardly along the horns 5, 5, where it is extinguished by the width of the gap that separates them, but, as a matter of fact, on lines that carry a 45 heavy current, and particularly under a high potential, or when lightning strikes the line, an arc once formed is maintained till it does damage to the line. The cartridges 7 (see Fig. 5) are represented in the drawings as 50 metal shells 8, which contain powder or some other explosive 11, a plug 9 and a pin 10 that extends through the plug and into the powder.

55 A cartridge 7 is fastened in any suitable manner to each of the horns 5, 5 of the lightning-arrester shown in Fig. 1, so that if an

arc forms across the elbows 6, 6 of the horns, it moves upwardly and reaches the powder of the cartridge by means of the pins 10, 10, which momentarily become conductors constituting portions of the electric circuit. The flow of current between the inner end of each pin and the metal shell 8 then ignites the powder 11, thus causing an explosion that blows out the plug 9 and, with it, the 65 pin 10, thus breaking the arc.

While the arrangement just described has been proven to be effective, experiments have shown that a more powerful effect can be produced by fixing the cartridges in such a 70 position that when the explosion occurs the discharge from the cartridge will take a course across the arc. Such an arrangement of the cartridge is shown in Fig. 2. Here in place of the pin 10 I employ a longer conductor 12 which extends beyond the cartridge and is bent at an angle to the axis of the cartridge for the purpose of giving the arc more advantageous entrance to the powder. When the conductors 12, 12 are blown 75 out the gap between the horns 5, 5 is increased and the discharge from the cartridge is directly across the arc.

In Fig. 3 the post 13 with its insulator is 80 represented as having a number of upwardly-projecting "arcing points" 14 placed to catch an arc from the line wire 15. Here the cartridges 7 are placed on the upper ends of the points 14, so that an arc cannot reach one of the points without exploding a 85 cartridge.

90 Fig. 4 shows an arrangement similar to that shown in Fig. 3, except that the cartridges are connected by an "arcing ring" 95 16, such as are in common use on high-potential lines. Other arrangements of the horns or "arcing points" and the cartridges may obviously be made by any skilled electrician, and so I do not limit myself to those described.

100 I claim:—

1. The combination with an explosive cartridge of two elements one of which normally forms a portion of an electric circuit, an isolated conductor having one end seated 105 in the cartridge and insulated therefrom and its other end exposed and positioned adjacent the path of an arc between the two elements and adapted to form a path for said arc whereby the cartridge is exploded 110 to extinguish the arc.

2. An electric arc extinguisher having in

combination a cartridge containing explosive material and mounted upon one of two elements between which an arc may occur, said elements being electrically unconnected and one of the same normally forming a portion of an electric circuit, and an isolated conductor entering the explosive material and projecting from the cartridge so as to lie in the path of an arc occurring between the two conductors and to be expelled from said path when the cartridge is exploded.

3. The combination, with two conductors, of a cartridge containing explosive material and mounted on one of said conductors, with its open end projecting substantially at right angles to the path followed by an arc between said conductors, and a short isolated conductor having one end seated in the cartridge and its other end directed toward the second of said two conductors, whereby the isolated conductor is adapted to constitute a path for an arc and to be expelled from the arc in a direction substantially normal to the length of the arc.

25 4. The combination with two conductors of a cartridge containing explosive material, a short isolated conductor having one end seated in the cartridge and its other end exposed and positioned adjacent the path of an arc between the two first named conductors so as to form a course for such arc and adapted upon the occurrence of

such arc to be expelled by the explosive material from the path of the arc.

5. The combination with a line wire of a support therefor an insulator interposed between the wire and the support, said support provided with a plurality of arcing points spaced from the support and explosive means in connection with said arcing points for extinguishing an arc upon the occurrence thereof.

6. The combination with a line wire of a support therefor an insulator interposed between the wire and the support, said support provided with a plurality of arcing points, an arcing ring electrically connecting the arcing points and explosive means in connection with said points for extinguishing an arc upon the occurrence thereof.

7. The combination with a line wire of an insulator carrying the same, a support for the insulator, an explosive cartridge positioned intermediate a portion of the line wire and the support and adapted to be exploded upon the occurrence of an arc between the line wire and its supporting elements to automatically and immediately extinguish an arc.
